UNITED STATES PATENT OFFICE.

JOSEPH H. BOURGON, OF DETROIT, MICHIGAN, ASSIGNOR TO THE STUDEBAKER CORPORATION, OF SOUTH BEND, INDIANA, A CORPORATION OF NEW JERSEY.

DOOR BUFFER.

Application filed June 14, 1924. Serial No. 720,101.

This invention relates to vehicle body hardware and particularly to means for preventing the sagging and rattling of vehicle doors, such means being commonly known as door dove-tails.

An object of the present invention is to provide a door dove-tail of novel design and of simple and improved construction.

Another object is to provide a dove-tail in which the male member will present a multiplicity of wearing surfaces.

Still another object is to provide a door dove-tail in which the male member comprises a resilient metallic roller suitably confined in a housing and adapted to co-operate with a non-resilient female member, the roller being loosely confined in said housing when not in engagement with the female member.

The above being among the objects of the present invention, the same consists of certain features of construction and combination of parts to be hereinafter described with reference to the accompanying drawing and then claimed, having the above and other objects in view.

In the drawing, which illustrates a suitable embodiment of the present invention, and in which like numerals refer to like parts throughout the different views,

Figure 1 is a fragmentary perspective view of part of an automobile, showing the manner of mounting the dove-tail embodying the present invention thereon.

Figure 2 is a fragmentary perspective view of that part of the door striker plate in which the female member of the dove-tail is formed.

Figure 3 is a perspective view of the assembled male member of the dove-tail.

Figure 4 is a perspective view showing the male and female members of the dove-tail in operative position.

Figure 5 is a perspective view of the housing of the male member only.

Figure 6 is a perspective view of the metallic ring of the male member.

Figure 7 is a perspective view of the rubber plug of the male member.

Figure 8 is a section taken in a vertical plane through the members in operative position as shown in Figure 4.

As understood by those familiar with this art, door dove-tails are used for preventing vertical movement of the free edge

of a door in relation to the co-operating door frame, and comprise essentially a male and female member. One of the members is secured to the free edge of the door and the other is secured to the co-operating door frame member, and are such that when the door is closed the male member fits into or co-operates with the female member and thereby prevents vertical movement of one in respect to the other.

Although it is immaterial in the present invention which member is secured to the door or door frame, I have shown in the drawing the female member 9 on the door frame 10, it being formed integral with the door striker plate member 11 which may be of cast construction and adapted to extend substantially the full length of that side of the door frame 10, and which also serves to provide a striker plate 12 for the door lock 13. The female member 9 formed in the door striker plate member 11 is composed only of the walls surrounding the recess 9 in the member 11, the recess opening out on the side adjacent the free edge of the door 14 and also on the outside face of the member 11. The upper and lower walls of the recess converge slightly towards the inner end and the outside corners are rounded off to guide the male member thereinto when the door 14 is swung into closed position.

The male member is secured to the free edge of the door 14 in such a manner as to co-operate with the female member 9 and is composed of a casing member, a split metallic ring 15, and rubber plug or roller 16. The casing member is composed of a flat plate portion 17 provided with two perpendicularly extending arms 18 connected across their projecting ends by a web 19. A circular opening 20 extends through the plate 17 between the arms 18, and the inside faces of the latter are formed to a shape corresponding with the sides of the opening 20, that is to say, formed to the shape that would result if a reamer were passed through the opening 20 from the back of the plate 17 up to the web 19, removing metal from about the edge of the opening 20 and the inside faces of the arms 18. The rubber plug 16 which is of slightly larger diameter than the inside diameter of the split ring 15, is inserted in the latter, causing the same to expand slightly and hold the plug 16 therein. The outside diam-

eter of the split ring 15 thus expanded by the rubber plug 16 is preferably of slightly less diameter than the diameter of the opening 20 and is adapted to be inserted in the opening 20 and confined therein and between the arms 18, and is of slightly less length than the distance from the inside face of the web 19 to the rear face of the plate 17, so that normally the ring 15 and plug 13 form a loosely mounted roller confined within the arms 18 and which projects a substantial amount above and below the upper and lower edges of the arms 18. The split ring 15 is therefore free to rotate between the arms 18 when not in operative engagement with the female member 9 whose upper and lower faces are spaced a less distance apart than the normal diameter of the split ring 15.

20 The plate 17 is secured to the free edge of the door 14 by screws 21 or by other suitable means in such a position that the ring 15 will enter the female member 9. The plate 17 is preferably set into the free edge of the door 15 so that the front face of the plate 17 is flush with the edge of the door. As before stated, the normal diameter of the ring 15 is greater than the vertical distance between the upper and lower faces of the recess forming the female member 9, and when the door 14 is swung into closed position the ring 15 is forced into the female member and is distorted or flattened thereby, causing it to increase in width and firmly grip the inner curved faces of the arms 18. The rubber plug 16 has the effect of giving body or resistance to the distortion of the ring 15, and when forced into the female member 9, it is prevented from vertical movement in relation to the door 14 by reason of engaging the inner curved faces of the arms 18 and is also held from vertical movement in relation to the door frame member 10 by its engagement with the female member 9, and thus prevents any vertical movement of the free edge of the door 14 in relation to the door frame member 10 when the door 14 is in closed position.

50 Although the female member is shown incorporated as part of the striker plate member 11 it is evident that it is immaterial whether it is formed in the manner shown or is composed of a piece entirely separate and distinct by itself as in most of the conventional constructions and I do not limit my invention to the construction shown.

An important advantage of the construction shown is that the ring 15 is loosely mounted in its support and is free to rotate when not in operative engagement with the female member 9, and inasmuch as it is commercially impossible to so correctly hang the doors that the dove-tail members will exactly match each other when the door is

closed, it is evident that one side of the ring 15 will usually contact with one of the faces of the recess 9 before the other side does, thereby causing a slight rotary movement of the ring 15, with the result that the wear on the ring caused by its contact with the female member will be distributed over its entire surface and will not be limited to a particular spot as in the majority of conventional constructions.

It is evident that the dove-tail covered herein is of a simple, effective construction and one that is relatively economical to build, also the ring and rubber plug can readily be replaced should the same become worn or destroyed. While I have shown and described the male and female members as castings it is to be understood that the same can be formed of stampings or by other suitable means and that the shape can be varied to meet the requirements incidental to such changes or the form necessary in different automobile bodies. Also other formal changes may be made in the specific embodiment of the invention described without departing from the spirit or substance of the broad invention, the scope of which is commensurate with the appended claims.

What I claim is:

1. A door dove-tail comprising a non-resilient member having a recess formed therein and a second member, said second member comprising a casing, and a resilient roller loosely mounted within the casing and projecting above and below the same to engage the side walls of the said recess.

2. In a device of the class described, cooperating members comprising a male member having a frame and a resilient roller loosely mounted therein and projecting above and below the walls of said frame and a female member provided with a recess having non-resilient walls to receive said roller, said roller on engagement with said walls of said recess being expanded in one direction to engage said frame.

3. In a door dove-tail, a female member provided with a recess having non-resilient walls, a male member provided with a resilient member normally loosely confined between two arms and projecting above and below the same, said resilient member being compressed between the walls of said recess and expanded into close contact with said arms when in engagement with said recess.

4. In a device of the class described, a pair of members comprising a door and a door frame, a member provided with a recess secured to one of the first mentioned members, and a member secured to the other of said first mentioned members, said last named member providing a cage for loosely confining a resilient part, said part being adapted to be distorted upon engagement of said last named members whereby said mem-

bers are held from movement relative to each other.

5. In an automobile body having a door and a door frame, a member having a recess therein secured to one of said parts, a plate having a plurality of arms connected across their ends secured to the other of said parts, a resilient roller confined within said arms and projecting outwardly therefrom, said recess having non-resilient walls to receive said roller and distort the same into contact with said arms.

10. In a vehicle body having a door and a door frame, a plate having a plurality of curved arms connected across their ends secured to said door, an opening in said plate corresponding to the distance between said curved arms, a resilient member mounted in said plate and retained therein by said open-

ing and said arms, and a member mounted on said door frame and provided with a recess therein having non-resilient walls positioned to receive said resilient member and distort the same into frictional contact with said curved arms.

15. In a device of the class described, co-operating members comprising a male member having a frame and a resilient roller loosely mounted therein and free to revolve, and a female member provided with a recess adapted to receive said roller, said roller upon operative engagement with said recess being expanded into direct engagement with said frame and thereby locked against further rotative movement.

Signed by me at Detroit, Michigan, U. S. A., this 5th day of June 1924.

JOSEPH H. BOURGON.
